UNITED STATES PATENT OFFICE.

JOSEPH F. JECKERT, OF GARFIELD, NEW JERSEY.

SMOKER'S KIT.

1,227,444.

Specification of Letters Patent.

Patented May 22, 1917.

Application filed November 10, 1916. Serial No. 130,662.

To all whom it may concern:

Be it known that I, JOSEPH F. JECKERT, a citizen of the United States, residing at Garfield, in the county of Bergen and State of New Jersey, have invented new and useful Improvements in Smokers' Kits, of which the following is a specification.

The present invention is a smoker's kit, designed for holding cigars, tobacco, matches, and especially a lighted pipe which the user desires to lay aside for the moment; and the object of the same is to so construct a metallic holder for these various articles that it will be most convenient to the user and the disagreeable results from laying down a lighted pipe will be avoided.

This object is carried out by my invention whose details are explained below and illustrated in the drawings wherein—

Figure 1 is a perspective view of the device in use with its door open to expose a bag of tobacco.

Fig. 2 is a horizontal section, and

Fig. 3 is a vertical section.

By preference this cigar holder is made of metal, such as tin or the like, suitably treated by painting or more preferably japanning, and its size, shape, and exact detailed construction are matters of no moment. While it is designed to contain cigars, tobacco, and matches, the use of the receptacles for these articles is optional as its chief purpose is to support a lighted pipe or several of them. The holder comprises an upright back plate 1 having suitable means (not shown) for attaching it to an upright such as a wall, two ends 2 secured to and extending forward from the side edges of said back, a flat bottom 3 connecting the lower edges of the ends, and a front door 4 hinged at 5 to the front edge of the bottom, having a match scratching surface 6 on its exterior, and held normally closed by means of a spring 7 as best seen in Fig. 3. The ends 2 are reduced in width at their upper portions as at 2', and the front edges of the narrow portions are connected by a corrugated panel 8 whose corrugations are upright so as to produce channels between them at both

the front and the rear of the panel. This panel may well be made of corrugated sheet metal in strip form, attached at its ends to

the front edges of the end pieces 2', braced at intervals from the back by upright partitions 9, and supported at its lower edge upon a shelf 10 which extends forward from the back 1; and thus are produced channels or compartments for cigars which may stand upright therein as best seen in Fig. 1. The front edge of the shelf may well be bent downward into a tray 11 having a substantially upright rear wall and carried forward at its lower edge between the wide portion of the end pieces or plates 2, and turned upward at its front edge into a flange 12—all as best seen in Fig. 3. To the end pieces are preferably attached pockets 13 for matches and the like. The method of forming the various members and of connecting them where they meet each other is immaterial.

In use the appliance is hung on an upright such as the wall, and the user may insert cigars in the pockets behind the corrugated panel 8, matches in the pockets 13, and bags of tobacco in the receptacle which is exposed when the front door 4 is opened. But the peculiar location of the corrugated panel 8 is such that if the bowl of a pipe P be laid in the tray 11 and its stem S stood upright in one of the channels in this plate, it will remain in this position as seen in Fig. 1. The result is that the nicotine, oil of tobacco, and other juices which are within the bore of the stem will run down the same into the bowl, the loose ashes in the latter will fall out into the tray, and the mouth-piece of a pipe of ordinary length will rise above the panel 8 so that it comes into contact with nothing whatever. Cleanliness is therefore preserved, at any moment the pipe is ready for renewed use, and the surplus and cold ashes are automatically removed. In fact the tray may be used by the smoker to knock off the ashes into, either from the pipe or the cigars.

From the foregoing description, taken in connection with the accompanying drawings, the construction and manner of operation of the device will be clearly understood, and therefore a more extended explanation has been omitted.

What is claimed is:—

The herein described smoker's kit including an upright flat back and ends, the latter

being reduced in width at their upper portions, a corrugated panel connecting the front edges of said ends, the corrugations providing upright channels in front and in
5 rear of the panel, a shelf between said ends extending forward from the back beneath the panel and closing the lower ends of all

channels, the shelf being bent downward and thence forward into a tray, and an upright flange at the front edge of said tray, ¹⁰ the whole as and for the purposes described.

In testimony whereof I affix my signature.

JOSEPH F. JECKERT.
